(57) **CLAIM**

We claim, the ornamental design for a compression clamp, as shown and described.

DESCRIPTION

FIG. 1 is a perspective view of a compression clamp showing the new design;

FIG. 2 is a left sided view thereof;

FIG. 3 is a right sided view thereof;

FIG. 4 is a front view thereof;

FIG. 5 is a back view thereof;

FIG. 6 is a top view in a closed clamp configuration thereof;

FIG. 7 is a bottom view in the closed clamp configuration thereof; and,

FIG. 8 is a top view in an open clamp configuration thereof. The broken lines illustrate portions of the compression clamp and form no part of the claimed design.

1 Claim, 6 Drawing Sheets
